RAILWAY SIGNALING

Original Filed Feb. 18, 1930 2 Sheets-Sheet 2

INVENTOR:

P. P. Stoker,
by A. Z. Vencill
His attorney

UNITED STATES PATENT OFFICE

PAUL P. STOKER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed February 18, 1930, Serial No. 429,283. Renewed January 18, 1932.

My invention relates to railway signaling, and particularly to signaling for stretches of single track over which traffic moves in both directions. One feature of my invention is the provision, in signaling of this kind, of means controlled from a remote point for permitting several cars or trains to pass through a stretch in the same direction, while preventing two cars or trains moving in opposite directions from occupying the stretch at the same time. 55

I will describe one form of signaling apparatus embodying my invention, and will then point out the novel features thereof in claims. 60

15 In the accompanying drawings, Figs. 1^a and 1^b, when placed end to end with Fig. 1^a on the left, constitute a diagrammatic view showing one form of signaling apparatus embodying my invention. 65

20 Referring to the drawings, the reference character N designates a stretch of railway track between points X and Y, which track is divided by insulated joints to form a plurality of track sections X—1, 1—2, . . . 7—Y. 70

25 Located in the section X—1 is a switch L¹ leading into a passing siding P, and located in the section 7—Y is another switch L² leading into a passing siding Q. 75

30 Each track section is provided with the usual track circuit, comprising a track battery 8 and a track relay designated by the reference character T with a distinguishing exponent. 80

Traffic entering the stretch X—Y from the 35 left is governed by two signals S¹ and S^{1a}, according as such traffic enters from the main track N or the siding P. Traffic entering the stretch from the right is governed by two similar signals S² and S^{2a}, according as such 85

40 traffic is on the main track or the siding Q. 90

Located at the left-hand end of the stretch 45 X—Y is a despatcher's relay D¹, which is controlled by a selector K¹, and which selector is in turn controlled from a remote point, such as a despatcher's office, over a despatcher's line M. When the selector K¹ receives the code to which it responds, it will close a pick-up circuit for relay D¹, which circuit passes from terminal B of a suitable source 95

50 of current, through the selector K¹, and the 100

winding of relay D¹ to terminal O of the same source of current. When relay D¹ becomes energized, a stick circuit for this relay will become energized, which circuit is from terminal B, through the selector K¹, front contact 19 of relay D¹, and the winding of relay D¹ to terminal O. Relay D¹ will then remain energized until a code is transmitted over the line M to operate the selector K¹ in such manner as to open the stick circuit for this relay. 60

Associated with the switch L¹ is a switch repeater relay C¹, which is controlled by a pole-changer 31 operated by the switch L¹ in such manner that the relay is energized in normal or reverse direction according as the switch is in its normal or reverse position, but that the relay is momentarily deenergized during the transit of the switch from either position to the other. The circuit for the relay C¹ will be obvious from the drawings. 70

The apparatus for controlling the signals S¹ and S^{1a} involves a directional relay A¹, a home relay H¹, two slow-releasing relays E¹ and E^{1a}, and a stick relay G¹. 75

The right-hand end of the stretch X—Y is provided with apparatus similar to that just referred to for the left-hand end, and the parts of this apparatus bear the same reference characters except that they are provided with the exponent 2 instead of the exponent 1. 80

The operation of the apparatus is as follows:

I will first assume that there is a train 85 moving toward the right and approaching the stretch X—Y on the main track N, and that the despatcher desires to clear the signal S¹ to admit this train into the stretch. To do this, he will send the proper code over the transmission line M to operate the selector K¹ in such manner as to energize the despatcher's relay D¹. Directional relay A¹ will then become energized by virtue of a circuit which passes from terminal B, through the back point of contact 9 of the despatcher's relay D¹ at the right-hand end of the stretch, contacts 10 to 17, inclusive of track relays T⁸ to T¹, inclusive, front point of contact 18 of relay D¹, and the winding of relay A¹ to terminal O. Home relay H¹ will then be- 95

come energized, by virtue of a circuit which passes from terminal B, through contact 20 of track relay T⁴, contact 21 of relay T³, front point of contact 22 of a home relay H³ associated with an intermediate signal S³, contacts 23 and 24 of track relays T² and T¹, respectively, contact 25 of relay A¹, contact 26 of relay D¹, winding of relay H¹, and front point of contact 27 of relay H¹ to terminal O.

10 Assuming that switch L¹ is in the normal position, signal relay E¹ will then become energized, the circuit being from terminal B, through contact 28 of relay H¹, neutral contact 29 of switch repeater relay C¹, polar contact 30 of this relay in the left-hand position, and the winding of relay E¹ to terminal O. Signal S¹ will then be moved to the clear position by virtue of a circuit which includes front contact 34 of relay E¹.

15 When the train enters section X—1, it will open track relay T¹, and this will in turn open the circuits for directional relay A¹ and home relay H¹. The opening of home relay H¹ will, of course, open the circuit for signal relay E¹, with the result that signal S¹ will return to its stop position. During the time interval between the opening of track relay T¹ and the opening of signal relay E¹, however, a pick-up circuit for stick relay G¹ 20 will become closed, which circuit is from terminal B, through back contact 32 of track relay T¹, front contact 33 of relay E¹, and the winding of relay G¹ to terminal O. Relay G¹ is provided with two stick circuits, the first of which is from terminal B, through front contact 34 of despatcher relay D¹, back contact 35 of directional relay A¹, front contact 37 of relay G¹, and the winding of this relay to terminal O. The other stick circuit 25 for relay G¹ is from terminal B, through back contact 36 of switch repeater relay C¹, back contact 35 of relay A¹, front contact 37 of relay G¹, and the winding of relay G¹ to terminal O. It will be seen, therefore, that 30 after relay G¹ becomes energized, it will remain energized as long as the despatcher's relay D¹ remains closed, or if the despatcher's relay D¹ is opened, relay G¹ will remain energized during transit of the switch L¹ if this switch should be reversed. When relay G¹ is energized, it closes a branch around contact 25 of relay A¹ in the circuit for home relay H¹, so that after the train moving toward the right passes point 4, or such other 35 point as to permit relay H³ to become energized, home relay H¹ will again become energized thereby again energizing signal relay E¹ with the result that signal S¹ will return to the proceed position, thereby permitting a following train moving toward the right to 40 enter the stretch X—Y.

If the train moving toward the right is on the siding P, the despatcher will, of course, reverse switch L¹ to allow this train to pass 45 into the stretch of single track, and this will

reverse switch repeater relay C¹, thereby causing polar contact 30 of this relay to swing to the right. This will result in energizing signal relay E^{1a} instead of relay E¹, so that signal S^{1a} will move to the proceed position. The circuit for this signal is omitted from the drawings to simplify the disclosure.

The purpose of the stick circuit for relay G¹ controlled by contact 34 of the despatcher's relay D¹ is, of course, to permit following trains moving toward the right to enter the stretch X—Y without requiring any action on the part of the despatcher. The purpose of the other stick circuit for relay G¹ is to permit switch L¹ to be moved from the normal to the reverse position or vice-versa after the apparatus has been set up to permit a train moving toward the right to enter the stretch X—Y.

If the despatcher desires to admit a train moving toward the left into the section X—Y, he will transmit the code to which the selector K² responds, thereby causing relay D² to become energized. Directional relay A² will then become energized by virtue of a circuit which passes from terminal B, through the back point of contact 18 of the despatcher's relay D¹, then through the front contacts of the several track relays T¹ to T⁸, inclusive, front point of contact 9 of relay D², and the directional relay A² to terminal O. The operation of the remaining parts of the apparatus associated with the right-hand end of the stretch will be understood from the foregoing without detailed explanation.

Although I have herein shown and described only one form of signaling apparatus embodying my invention, it is understood that various changes and modifications may be made therein within the scope of the appended claims without departing from the spirit and scope of my invention.

Having thus described my invention, what I claim is:

1. In combination, a stretch of railway track along which traffic moves in both directions, such stretch being divided into sections each of which is provided with the usual track circuit including a track relay, a normally deenergized despatcher's relay, means controlled from a remote point for energizing said despatcher's relay, a directional relay controlled by a front contact of said despatcher's relay and a front contact of each of said track relays, a home relay, a circuit for said home relay including a front contact of said despatcher's relay and a front contact of said directional relay as well as a front contact of the track relay for the first track section in said stretch, a slow-releasing signal relay controlled by a front contact of said home relay, a signal governing traffic into said stretch and controlled by said signal relay, a normally deenergized stick relay, a pick-up circuit for said stick relay including

a back contact of said first section track relay and a front contact of said signal relay, a stick circuit for said stick delay including a back contact of said directional relay and a 5 front contact of said despatcher's relay, and a branch for said home relay circuit around the front contact of the directional relay and including a front contact of said stick relay.

2. In combination, a stretch of railway 10 track along which traffic moves in both directions, such stretch being divided into sections each of which is provided with the usual track circuit including a track relay, a switch leading from a siding into the first 15 section of said stretch, a switch repeater relay controlled by said switch and energized while the switch is in normal or reverse position but deenergized during transit of the switch, a normally deenergized despatcher's 20 relay, means controlled from a remote point for energizing said despatcher's relay, a directional relay controlled by a front contact of said despatcher's relay and a front contact of each of said track relays, a home relay, a 25 circuit for said home relay including a front contact of said despatcher's relay and a front contact of said directional relay as well as a front contact of the track relay for the first track section in said stretch, a slow-releasing 30 signal relay controlled by a front contact of said home relay as well as by a front contact of said switch repeater relay, a signal governing traffic into said stretch through said switch and controlled by said signal relay, a 35 normally deenergized stick relay, a pick-up circuit for said stick relay including a back contact of said first section track relay and a front contact of said signal relay, a first stick circuit for said stick relay including a back contact of said directional relay and a front contact of said despatcher's relay, a second stick circuit for said stick relay including a back contact of said directional relay and a back contact of said 40 switch repeater relay, and a branch for said home relay circuit around the front contact of the directional relay and including a front contact of said stick relay.

3. In combination, a stretch of railway 45 track along which traffic moves in both directions, such stretch being divided into sections each of which is provided with the usual track circuit including a track relay, a normally de-energized despatcher's relay, 50 means controlled from a remote point for energizing said despatcher's relay, a directional relay, means for energizing said directional relay when said despatcher's relay is energized provided said stretch is unoccupied, a home relay, means for energizing said home relay when said despatcher's relay and said directional relay are energized provided the first section in said stretch is unoccupied, a slow-releasing signal relay 55 controlled by a front contact of said home

relay, a signal governing traffic into said stretch and controlled by said signal relay, a normally deenergized stick relay, means for energizing said stick relay when a train enters said first section provided said signal relay is energized at the time, means for subsequently keeping said stick relay energized as long as said despatcher's relay remains energized, and means operating when said stick relay is energized to remove said home 70 relay from control by said directional relay.

4. In combination, a stretch of railway 75 track along which traffic normally moves in both directions, such stretch being divided into sections each of which is provided with the usual track circuit including a track relay, a switch leading from a siding into the first section of said stretch, a normally deenergized despatcher's relay, means controlled from a remote point for energizing said despatcher's relay, a directional relay, means for energizing said directional relay when said despatcher's relay is energized provided said stretch is unoccupied, a home 80 relay, means for energizing said home relay when said despatcher's relay and said directional relay are energized, provided the first section in said stretch is unoccupied, a slow-releasing signal relay controlled by a front contact of said home relay, a signal governing traffic into said stretch and controlled by said signal relay, a normally deenergized stick relay, means for energizing said stick relay when a train enters the said first section provided said signal relay is energized 85 at the time, means for subsequently keeping said stick relay energized as long as said despatcher's relay remains energized, other means for keeping said stick relay energized during transit of said switch, and means operating when said stick relay is energized to remove said home relay from control by 90 said directional relay.

In testimony whereof I affix my signature.
